DESIGN FOR AN EARRING

Otto Grun, New York, N. Y.

Application December 11, 1944, Serial No. 116,837

Term of patent 14 years

(Cl. D45—9)

To all whom it may concern:

Be it known that I, Otto Grun, a citizen of the United States, residing in the Borough of Manhattan, city, county, and State of New York, have invented a new, original, and ornamental Design for an Earring, of which the following is a specification, reference being had to the accompanying drawing, forming part thereof.

On the drawing,

Fig. 1 is a front elevational view of an earring embodying my design;

Fig. 2 is a side elevational view of the earring

shown in Fig. 1, the ear-clasping device being shown in ear-clasping position;

Fig. 3 is a rear elevational view of the earring as it appears in Figs. 1 and 2;

Fig. 4 is a vertical cross-sectional view, substantially on the line 4—4 of Fig. 5; and

Fig. 5 is a view similar to Fig. 3, the ear-clasping device being shown open.

I claim:

The ornamental design for an earring, as shown.

OTTO GRUN.
